UNITED STATES PATENT OFFICE

146,986

DESIGN FOR A CANDLE AND FLOWER HOLDER

Jeanne T. Purcell, Bern Township,
Berks County, Pa.

Application October 31, 1945, Serial No. 123,344

Term of patent 14 years

(Cl. D48—2)

To all whom it may concern:

Be it known that I, Jeanne T. Purcell, a citizen of the United States, residing at Bern Township, in the county of Berks and State of Pennsylvania, have invented a new, original, and ornamental Design for Candle and Flower Holder, of which the following is a specification, reference being had to the accompanying drawing, forming part thereof.

Fig. 1 is a perspective view of a candle and flower holder embodying my design.

Fig. 2 is a plan view of the same.

Fig. 3 is a side elevation thereof.

Fig. 4 is a cross-sectional view taken on the lines 4—4 of Fig. 2.

Fig. 5 is bottom plan view.

What I claim is:

The ornamental design for a candle and flower holder, as shown.

JEANNE T. PURCELL.
